UNITED STATES PATENT OFFICE.

JOHN E. BOYCE, OF YONKERS, NEW YORK, ASSIGNOR TO OTIS ELEVATOR COMPANY, OF JERSEY CITY, NEW JERSEY, A CORPORATION OF NEW JERSEY.

SELF-LEVELING ELEVATOR.

Application filed February 14, 1923. Serial No. 618,897.

To all whom it may concern:

Be it known that I, JOHN E. BOYCE, a citizen of the United States, residing in

Yonkers, in the county of Westchester and 5 State of New York, have invented a new and useful Improvement in Self-Leveling Elevators, of which the following is a specification.

My invention relates to an improved controlling apparatus for use in control systems for electric elevators commonly called 10 the self-leveling type of electric elevator, wherein the car is invariably brought to a stop level with the landing.

15 An object of the present invention is to provide an improved controlling mechanism in the above mentioned type of electric elevator for controlling the operation of stopping the elevator and the car invariably 20 level with the landings.

A further object of the present invention is the provision of novel means for operating the improved controlling mechanism to stop the elevator should the improved controlling mechanism fail and not operate 25 properly, as of first intention, to control the operation of stopping the car and the subsequent stop of the car level with a landing.

Still further objects of the present invention 30 will appear hereinafter in this specification.

In the drawings accompanying this specification, Figure 1 illustrates a rear elevation view of the improved controlling mechanism.

Figure 2 illustrates a sectional side view in elevation of an electro-magnet form of the improved controlling mechanism.

Figure 3 illustrates a sectional side view in elevation of an electric motor form of the improved controlling mechanism.

Figure 4 illustrates another view in elevation, part fragmentary and sectional of the electric motor form of mechanism.

45 Figure 5 illustrates still another view of the electric motor form of mechanism.

Figures 6, 7, 8 and 9 represent in detail the various positions of some of the parts of the mechanism.

50 Figure 10 represents a view of the operating shaft of the mechanism.

Figure 11 is an end view of the shaft.

Figure 12 is an end view of a bushing on the shaft of Figure 10.

Figure 13 is a view of the plunger of the 55 magnet in the form of mechanism shown in Figure 2.

Figure 14 is an end view of the plunger in Figure 13.

Figure 15 represents the part broken off 60 of the Figure 2.

Figure 16 represents a wiring diagram of a system of electrical circuits embodying diagrammatically the electric motor form of the present invention which may be used 65 to control an electric elevator.

Similar reference characters refer to similar parts throughout the several views.

This invention of an improved controlling mechanism adapted to control the operation 70 of stopping the elevator and stopping the car level with the landings, is positioned in the elevator well, as for instance on top of the car.

Referring to the drawings, the macha- 75 nism comprises a switch case 1 which together with a cover 2 of the switch case encloses the switches and also certain other parts of the controlling mechanism. The switches are designated 3, 4, 5 and 6, and are 80 held by rods 7 and 8 in the switch case. Each switch comprises a movable arm 9 carrying an electrical contact 10 at one of its ends, adapted to make electrical contact with another electrical contact 11 of the 85 switch when it is moved to closed position, and the arm 9 also carrying at its other end a roller 12. A spring 13 of the switch moves the arm 9 to the closed position of the switch. A shaft 14, held in journals 15 90 formed on the side of the switch case 1, carries on it and within the switch case a plurality of cam members 16, 17, 18 and 19, and outside of the case, the shaft carries two roller arms 20 and 21, the arms each carry- 95 ing a roller 22 at its free end. The roller arms 20 and 21 extend out into the car hatchway and, from the top of the car where the mechanism is positioned, into the path of groups of cams A and B. Each 100 group of cams comprises a cam 23 and a cam 24 that are affixed to a side of the elevator well within the proximity of each floor landing, there being a cam group for each landing. With the car in motion, and it is desired that it be stopped at a predetermined floor landing, the roller arms 20 and 21 are caused at the proper time during

the approach of the car to the landing, to assume a position such that the rollers 22 of the arms will be in the path of the cams 23 and 24 of the cam group; the roller 22 on one arm will, at a time depending upon the direction of the travel of the car, consequently strike its corresponding cam of the cam group of the desired floor landing, causing an operation of certain two of the 10 switches of said controlling mechanism, the first switch to operate effecting a slowing down of the elevator and the second switch to operate effecting the stopping of the car level with the desired floor landing.

15 Referring to Figure 2, the form of controlling mechanism shown therein comprises an electro-magnet C placed on the switch case 1 as shown, composed of a magnet coil 25 with a plunger 26 for the coil, which magnet 20 coil when energized pulls the plunger up into the coil, the movement of the plunger serving to operate the switches of the controlling mechanism, as will be explained more fully hereinafter. When the magnet 25 coil is deenergized, it releases its hold on the plunger which consequently drops due to gravity to its original normal position shown in Figure 2. When the plunger 26 is in its normal or released position as shown 30 in Figure 2, it rests on a stop bolt 50 in the switch case 1 that is adjustable and, therefore, the length of the drop of the plunger is adjustable, the bolt being held in adjusted position by a nut 51 thereon and bearing on the bottom side of the switch case. The cam members, 16, 17, 18 and 19 are mounted on the shaft 14, as before stated, the cam members 16 and 17 being directly carried on a bushing 27 journaled on the shaft 14. The 40 cam members are respectively clamped to the shaft and bushing by a bolt 28 in each cam member and held from turning on the same by a set screw 29 also in each cam member, which screws are screwed down into cone shaped seats in the periphery of the bushing and shaft as shown in Figures 10, 11 and 12. To the bushing 27 is keyed, the roller arm 20, and to the shaft 14 is keyed the roller arm 21; movement of either roller arm separately will only move the cam members keyed, so to speak, to the roller arm moved, the cam members 16 and 17 being moved when the roller arm 20 is moved, and the cam members 18 and 19 being moved 50 when the roller arm 21 is moved: movement of both roller arms at one and the same time will move all of the cam members. The movement of the cam members closes the switches of the controlling mechanism or permits them to close, as the case may be, as will be explained hereinafter. The cam members 17 and 18 have each two switch operating arms; the switch operating arms of the cam member 17 being designated 30 and 31, and the switch operating arms of the 55 cam member 18 being designated 32 and 33; the arms 30 and 32 each carrying an adjustable bolt 80, and a nut 81 to hold the bolt fixed. The cam members 17 and 18 have also another operating arm 34 and 35, respectively, each arm adapted normally to rest one on a seat 36 and the other on a seat 37, of the plunger 26 (see Figure 13) of the electro-magnet form of the controlling mechanism. Each cam member 17 and 18 has also parts, 38 and 39, that carry in an opening that is clear through them a rod block 40 and a rod block 41 respectively, which support the threaded end of each of two spring rods 42 and 43 respectively, each 60 spring rod carrying a spring 44 and 45 respectively, and supported at their other ends in the switch case 1 at points 46 and 47 respectively. There are nuts 48 and 49 on the threaded end of the rods 42 and 43, which hold the rod blocks in position on their rods, and the rod blocks hold the parts 38 and 39 in proper position, but more particularly hold in the proper position the switch operating arms of the cam members 90 with their respective switches. The cam members 16 and 19 are clamped to and held in place on the shaft 14 as described before. The number 16 comprises a switch-operating arm 52, and the cam member 19 comprises a switch-operating arm 53. The arm 52 is moved in one direction when the cam member 17 is moved by the plunger and the arm 53 is moved in one direction when the cam member 18 is moved by the plunger; and the arm 52 when moved operates the switch 3 and the arm 53 the switch 6, as will be explained hereinafter more in detail.

65 Referring to Figures 3, 4 and 5, they show the electric motor form of my improved controlling mechanism which form differs from the electro-magnet form in that an electric motor is substituted for the electro-magnet. In the Figures 3, 4 and 5, an electric motor D of the series type 105 is shown, which may be operated either by direct or alternating current. The motor is supported on a standard 54 and the standard on a base 55. Another standard 56, is also supported on the base, which latter is placed on the switch case 1, as shown. The motor has a shaft 57 upon which is a pinion gear 58 that meshes with another gear 59 keyed by a key 60 to a pinion gear 61 that is fast on a shaft 62, in the motor standard 54; the pinion gear 61 meshes with a gear 63 keyed by a key to a shaft 65 supported in the motor standards 54 and 56. A casing 66 encloses the gear end of the motor and the gears. Upon the shaft 65, between the motor standards 54 and 56, is a chain block 67 adapted to wind on and off a chain 68 fastened at one of its ends to the block and its other end to a plunger 69 that has 110

seats 70 and 71 upon which rest the operating arms 34 and 35 of the cam members 17 and 18. The motor when operated turns the pinion gear 58 on the shaft 57 of same, which gear causes the other gears to turn and the chain 68 is thereby wound on the block 67 and the plunger 69 is therefore pulled up and also the operating arms 34 and 35 of the cam members 17 and 18, respectively, the switch-operating arms of the cam members operating their respective switches of the mechanism as a result in a manner as will be explained hereinafter. A stop collar 72 on the shaft 65 arrests the motor in its operation, and consequently further movement of the gears and plunger 69. The stop collar is turned when the motor operates, from its position shown in the dotted lines, in Figure 5, against a stop 73 held in an arm 74 of the motor standard 56, to its position shown in dotted lines against a similar stop 75, also held in the arm 74, both stops being adjustable in the arm. The stop 75 comprises a plunger 76, a spring 77, and a plug 78, for holding the plunger and spring in place in a hollow cylinder 79 of the stop. The stop collar forces the plunger 76 down in the cylinder against the spring 77. When the stop collar is turned against the stop 75, as for example, in this instance, the motor D may be operated in a reverse direction to turn the stop collar from against the stop 75 to and against the stop 73. The stop 73 is similar to the stop 75. This form of stop furnishes a more or less noiseless one. As long as there is current on the motor, the stop collar will be held against the stop 75 and the plunger be held lifted. With the plunger 69 lifted and the stop collar 72 against the stop 75, and the current be then cut off from the motor, the plunger 69, by its weight and the weight of the operating arms 34 and 35 of the cam members 17 and 18 and the action of the springs 44 and 45 moving the cam members, will drop to the stop 50, and the stop collar, gears and motor will be turned in the direction opposite to the direction that they were turned by the motor when it turned the stop collar from the stop 73 to and against the stop 75, and the stop collar will engage the stop 73, and the plunger 69 rest on the stop bolt 50. The motor D is controlled to operate by the control mechanism for operating the elevator, and when the mechanism for starting the car is operated, the motor for operating cam members is operated.

Referring to the cam members 17 and 18, they are adapted to operate both of the two switches 4 and 5, as Figure 1 shows. The bolt 80 in the arms 30 and 32 of the cam members shown in the Figures 2, 3, 6 and 7 is omitted from the cam members in Figure 1, as is also the nut 81 that holds the bolt in each arm, in order that the Figure 1 may be more clear. In the electric motor form of the improved controlling mechanism, the cam members are first operated and they operate the switches in the following manner: Assuming that the motor D of the controlling mechanism has been operated, and as a result the plunger has lifted and cam members 17 and 18 are now in a position like the position of the cam member 17 in Figure 7, the cam members 16 and 19 are at this time in a position like the position of the cam member 16 in Figure 9, and the roller arms 20 and 21 in a position such that the roller 22 on each arm is on a line perpendicular with each other as shown in Figure 9. While the rollers 22 are in this position they are free of the cams 23 and 24 of the cam groups at the various floors, and the movement of the elevator car carries the rollers along a path between the cams. The switches 4 and 5 were held open before the operation of the motor D took place, the switch 4 by the arm 30 of the cam member 17, Figure 6, and the switch 5 by the arm 32 of the cam member 18, Figure 2. In the new position of the cam members 17 and 18, the switch 4 is held open by the arm 31 of the cam member 18, and the switch 5 is held open by the arm 33 of the cam member 17, the latter mentioned arms of the cam members being adapted to engage the roller 12 of each switch 4 and 5, as the former mentioned arms 30 and 32 leave the rollers, so that the rollers are not free to allow their switches to close. The cam member 16, now in its new position, see Figure 9, has allowed switch 3 to close, and cam member 19 has allowed switch 6 to close, but as the circuits to these switches are adapted to be opened at this time elsewhere in the elevator control system, the closing of switches 3 and 6 is of no consequence at present other than that they have closed. It will be assumed that the car is being moved in a down direction of car travel and it is desired that it be stopped at the floor where the cams 23 and 24, in Figure 7, are, which floor is of no consequence in this present description other than it is not a floor at the top limit of travel of the car. It will be further assumed that the car is within the near proximity of the floor, and the car operator being aware of the same brings his car control lever to the off or stopping position and cuts the power off from the hoisting motor, or if the car is adapted to be automatically controlled, such controlling mechanism will at this time cut off the power, the time in question of course being the proper time for either mechanism to operate. Such proper time for cutting off the power from the hoisting motor is when

the roller 22 on the arm 21, in this instance, is abreast of its cam 23, or so near the cam that the car in coasting will carry the roller of the roller arm up on to it, and as the power is adapted to be cut off from the motor D of the controlling mechanism, when the car or hoisting machine mechanism cuts the power off from the hoisting motor, the arm 21 is now free from holding its roller 22 in a perpendicular position, and will move its roller for engagement with the cam. The other roller arm 20 is now also free from being held, and because the cam 24 is not in the way of its roller 22 at this time, the roller arm 20 moves to its full free position. The cam members 16 and 17, fast to the bushing 27 that the roller arm 20 is keyed to, moved at this time to their normal positions as shown in Figures 8 and 6 respectively. The cam member 16 in moving opened its switch 3, while the cam member 17, by its arm 30 moving forward, so to speak, in the movement of the cam member, moves to a position to open its switch 4, see Figure 6, but finds that switch already opened by the arm 31 of the cam member 18, and the arm 33 moving backward, so to speak, and the same movement of the cam member 17, permits the switch 5 to close. With the switch 6 already closed, and the switch 5 now closed, they establish circuits to a fast speed switch and a directional switch for the elevator hoisting motor mechanism that the switches may operate and close circuits, either to one and the same hoisting motor for continuing the movement of the car and now adapted to operate at a greatly reduced speed, or to a second hoisting motor now adapted to operate at its fast speed, for it to continue the movement of the car. As the car continues moving down, in this instance, the roller 22 of the roller arm 21 rides on the vertical camming surface of the cam 23, keeping the switches 5 and 6 closed; finally the roller 22 rides off of the vertical camming surface, and if the roller arm 21 is going to function properly it will allow its roller 22 to follow the cam on its incline camming surface. As the roller 22 follows the incline camming surface of the cam, the arm 21 is being slowly moved over towards its normal or full free position.

The first movement, so to speak, of the roller 22 on the incline surface is adapted to permit sufficient movement of the arm 21 that it will cause the cam member 19 fast to the shaft 14 to which the roller arm 21 in question is also fast, to move, and open its switch 6 which will open a circuit to the fast speed switch and cause a slow down of the speed of the car, and later as the roller 22 continues moving on the incline camming surface of the cam and finally moves off of the cam the roller arm 21 has been moved

further towards its normal position and finally to its normal or full free position. The further movement of the roller arm has allowed the cam member 18, also fast to the shaft 14 that the arm itself is fast to, to open by its arm 32, the switch 5, it opening a circuit to the down directional switch of the hoisting motor allowing it to stop and also the car level with the desired landing. The speed of the car when controlled by the cams is of so small a value that the instant of cutting off of the power from the hoisting motor also brings a near or simultaneous stop of the car. The above description is of the normal operation of stopping the car level with the landing. If the controlling mechanism mentioned in the operation of stopping the car fails to or does not operate properly as of first intention to control the operation of stopping the car level with a landing, as related, for instance, should the roller 22 on the arm 21 by reason of some one fault or another remain in a position as if the roller were still projected to a line extended from the vertical camming surface of the cam instead of the roller following the incline surface of the cam as it is designed it shall do, to operate the switches to stop the car. Referring to Figure 7, it will be remembered that the switch 5 shown therein was closed in the operation of stopping the car at the landing, in the fact that its operating arm 32 on the cam member 18 was held back away from the switch by the roller arm 21 being held by its roller 22 against the cam 23, and because the other operating arm 33 of the switch on the cam member 17 that held it open previous to its closing was moved backward to allow the switch to close, and the operating arm 33 was moved backward to allow the switch to close by the movement of the roller arm 20 that operates it having been moved to its full free position as there was no cam 24 in the way of it and its roller. It will also be remembered that it was the operating arm 32 of the cam member 18 that was being moved forward when the roller of the roller arm 21 rode off of the vertical camming surface and on the incline camming surface of the cam 23 that opened the switch 5 to stop the car level with the landing. If the roller arm 21 remain in the position as if the roller 22 thereon was still riding on the vertical surface of the cam 23, the hoisting motor would be still getting current through the switch 5 and would pull the car past the floor, because the operating arm 32 of the cam member 18 adapted to be moved to open the switch 5 was not moved, and the operating arm 32 did not move because the roller arm 21 did not move, which is shown in Figure 7. The instant that the car proceeds past the landing, the roller arm 20, that is adapted to operate the controlling mechanism to

control the stopping of the car and stop it level with a landing after an up direction of travel of the car, will be moved. The roller arm, 20 in this instance of a down travel of the car, will be moved to its operative position by the roller 22 thereon contacting with the cam 24 as shown in Figure 7. And when the roller arm 20 is moved, so also is the cam member 17, that is fast to the bushing 27 that the roller arm 20 is fast to. The cam member 17 in moving will, by its operating arm 33,—which it will be remembered held open the switch 5 before it was closed—; open at this time the switch 5, and with the switch open the car will come to a stop. The car will have been stopped, of course, below the landing, and it cannot be brought back at this time to a level stop with the landing, as ordinarily the controlling mechanism will do, because the cam member 18 is still in its operative position, and the switch 4, adapted to be in a circuit to the up directional switch of the motor, is held open by the operating arm 31 of the cam member 18 by reason of the roller arm 21 not having followed the incline surface of the cam and moved to its full free position. The car stopping below the landing as described, or if it had stopped above the landing because the roller arm 20 had not moved properly, warns the car operator or the attendant in charge of the elevator that the controller mechanism is out of order and needs attention. The foregoing description of operation was of the electric motor form of the controlling mechanism; that form of mechanism differs from the magnet form of controlling mechanism only in the means employed to free the roller 22 on the roller arms 20 and 21 from the cams 23 and 24 in the elevator hatchway and move the arms to a perpendicular line with each other in order that the rollers 22 on the arms may not strike the cams at the floor landings at which it is not desired to stop the car; therefore, the foregoing description of the operation of the motor form of controlling mechanism is applicable as a description to the magnet form of controlling mechanism; and consequently it is unnecessary to rewrite a description of the operation of the magnet form of controlling mechanism.

A description of the operation of the electric motor operated form of the controlling mechanism embodied in a system of elevator control will now be written.

Referring to Figure 16, an elevator car E operated by a car control lever 82 is shown; movement of the lever to a position to the left will cause the car to descend, and the operation of the lever to the right will cause the car to ascend. Assuming that it is desired to cause the car to ascend, the control lever 82 is moved to the right which brings a contact segment 83 thereon in con-

tact with a contact 84 of the car switch that the lever is a part of, closing a circuit as follows: from the plus main, by wire 85, through the winding 86 of the up direction switch F of the motor M, by wire 87, contact 84, contact segment 83, by wire 88, to the minus main. As a result of closing this circuit the winding 86 pulls its plunger 89 up within itself and the plunger 89 affixed to the up-direction switch F closes the switch. A circuit is thereby closed to the motor M for it to cause the car to ascend. It is not thought necessary to trace out this circuit. By the switch F closing, a circuit to the motor D also is closed as follows: from the plus main, through the contact 90 and plate 91 of the up direction switch F, contact 92 of the switch F, wire 93, through the armature 94 and series field 95 of the motor D, by wire 96 and 110 to the minus main. The motor D now operates the cam members and the roller arms 20 and 21, as previously explained. The illustration of the controlling mechanism in the Figure 16 is diagrammatical, and it operates as follows: The motor D in operating turns the shaft and bushing supposedly to be the shaft 14 and bushing 27 in the other figures and they in turning suitably move the diagrammed cam members; the arm 52 of the cam member 16 in moving from under the switch 3 allows the spring 13 of the switch to close it, the arm 30 of the cam member 17 moves from under the switch 4, but as the arm 30 is followed up by the arm 31 of the cam member 18, the switch 4 is kept open by the arm 31; the other arm moves from under the switch 5 and is followed up by the other arm 33 of the cam member 17, so that the switch 5 is likewise kept open, and the arm 53 of the cam member 19 moving from under the switch 6 allows that switch to close. Though the switches 3 and 6 are closed, the circuit that they are in is at this time open at the contact 97 of the switch F; the plate 98 of the switch F is adapted to close the contact 97 with the contact 99 of the switch F, but at this time has been lifted off of the contacts 97 and 99 as the result of the winding 86 of the switch F drawing its plunger 89 up into itself. As the car nears the desired landing to be stopped thereat, the car control lever 82 is brought to a center or off position, thereby the circuit to the winding 86 of the up direction switch F is opened, and that switch opens and cuts the power off from the motor M. The up direction switch F in opening has also opened the circuit to the motor D which now allows the cam members to return to their normal positions, and the roller arms to their full free position. If the centering of the car control lever was made before the rollers reached the cams, 23 and 24, and the car coasts after

the power is cut off by the car control lever, and brings the roller 22 of the roller arm 20 into engagement with the cam 24 and the roller rides up on the cam, it will move its arm 20, which in time will cause the arm 52 of the cam member 16 to move from under the switch 3 and allow it to close and move the arm 30 of the cam member 17 from under the switch 4 allowing that switch to close; the other arm 33 of the cam member 17 has moved under the switch 5 to open it, but that switch is found to be already opened by the arm 32 of the cam member 18 as the roller arm 21 that operates the cam member 18 was allowed to swing to its full free position; the movement of the arm 33 of the cam member 17 and under the switch 5 was therefore at this time of no consequence. The arm 53 of the cam member 19 was also moved by the roller arm moving to its full free position. The arm 53 in moving opened the switch 6. Or again, if the car control lever is centered at the time, when the roller 22 of the arm 20 is abreast of the cam 24, the cam will not allow the arm 20 to swing to its full free position and consequently a result of the roller 22 of the arm 20 being on the cam, the arm 20 will close the switches 3 and 4 as described. The switch 3 in closing closed a circuit to the winding 100 of a fast speed switch G as follows: from the plus main, contact 97, plate 98, and contact 99 of the up direction switch F, they now being closed together, by wire 101, contact 102, plate 103 and contact 104 of the down direction switch H, by wire 105, junction point 106, by wire 107, through the winding 100 of the fast speed switch G, by wire 108, the now closed contacts of the switch 3, by wire 109, by wire 110, to the minus main. The switch 4 in closing closed a circuit as follows: from the plus main to junction point 106 as before, by wire 111, through the winding 112 of the up direction switch I of a motor M', by wire 113, through the now closed contacts of the switch 4, by wire 114, by wire 115, by wire 109 and by wire 110 to the minus main. Circuits are now closed to the windings 100 and 112 of the fast speed switch G and of the up direction switch I of the motor M', which windings operated their respective switches, and the switches in turn closed circuits for operating the motor M' at its fast speed.

The fast speed switch G in operating inserted a resistance 116 in circuit with the field 117 of the motor M' which serves to weaken the field and the fast speed of the motor is thereby obtained. It is thought not necessary to trace out the circuit to the armature of the motor M'. The fast speed of the motor M' is much lower than the speed of the motor M, and consequently while the car is being operated by the motor

M' at its fast speed the car is being moved only at a comparatively slow rate of speed. As the car is moving slowly and getting nearer to the landing all the time, the roller 22 on the roller arm 20 and on the cam 24 is slowly coming nearer the incline camming surface of the cam, and the first travel of the roller on the incline permits the roller arm to move further toward its normal position, which movement of the roller arm 20 moves the cam member 16 underneath the switch 3 which opens, opening the circuit to the fast speed switch G. The motor M' will now operate on a reduced speed and the speed of the car will be reduced. As the roller moves further on the incline camming surface of the cam in the movement of the car, the roller arm will eventually have moved far enough that it will operate the cam member 17, whose arm 30 will return to underneath the switch 4, which will open, opening the circuit to the winding of the up direction switch I which switch will open the circuit to the armature of the motor M' which stops and the car stops level with the landing.

Having thus described and illustrated my invention, what I claim is:

1. In a self-leveling elevator, leveling apparatus having means adapted to control the elevator to bring the car to a desired floor landing and stop it thereat level with the landing and emergency means to operate the first mentioned means and stop the elevator in case the first mentioned means fail to operate to stop the car at the landing.

2. In a self-leveling electric elevator, the combination of the leveling apparatus comprising a switch automatically operable for stopping the car level with a desired floor landing, and accessory means to operate said switch in case it fail normally to operate to stop the car.

3. In a self-leveling electric elevator, the combination of the leveling apparatus comprising a switch automatically operable for stopping the car level with a desired floor landing, and accessory means automatically operable to operate said switch in case it fail normally to operate to stop the car.

4. In a self-leveling electric elevator, the combination of the leveling apparatus comprising a switch automatically operable for stopping the car level with a desired floor landing and having accessory means automatically operable to operate said switch in case it fail normally to be automatically operated to stop the car.

5. In a self-leveling electric elevator, a car leveling apparatus comprised of a self closing car leveling switch and means adapted to be operated to open the switch and allow the elevator to stop with the car level with the desired floor landing and means adapted to be operated to open said switch

- in case the means first mentioned fail to open said switch.
6. In the self-leveling electric elevator art, a car leveling apparatus comprised of a self closing car leveling switch and movable arms, one arm adapted to be moved to open the switch and allow the elevator to stop with the car level with the desired floor landing and the other arm adapted to be moved to open said switch in case the arm first mentioned fail to operate to open the switch.
7. In the self-leveling electric elevator art, a car leveling apparatus comprised of a self closing car leveling switch and movable arms, one arm adapted to be moved to hold the leveling switch open, and subsequently allow the switch to close for the leveling operation of the car and the other arm adapted to be moved to open the switch to stop the car level with a desired floor landing, but in case the said other arm fail to be moved to open the switch, then the arm first mentioned to move to open said switch.
8. In a self-leveling electric elevator, the combination of the leveling apparatus comprising switches and sets of arms adapted to operate the switches, one set normally to operate the switches for stopping the car at a desired floor landing level therewith and the other set to operate said switches in case the first mentioned set of arms fail to operate the switches to stop the elevator.
9. In a self-leveling electric elevator, the combination of the car, a hoisting machine, the car switch, the leveling apparatus comprising a self closing leveling switch, and a member having a camming arm adapted to be moved against the leveling switch to hold the switch open during the time of control of the elevator by the car switch.
10. In a self-leveling electric elevator, the combination of the car, a hoisting machine, the car switch, the leveling apparatus comprising a self closing leveling switch, and a member having a camming arm adapted to be moved against the leveling switch to hold the switch open, said arm controlled by the car switch.
11. In a self-leveling electric elevator, the combination of the car, a hoisting machine, the car switch, the leveling apparatus comprising a self closing switch and a movable camming arm adapted to be moved against the leveling switch to keep it open during the time of control of the elevator by the car switch, and electro-motive means controlled by the car switch adapted to move the arm that keeps the leveling switch open.
12. In a self-leveling electric elevator, the combination of the car, a hoisting machine, the car switch, the leveling apparatus comprising self closing leveling switches, one for up direction of travel of the car and the other for down direction of travel of the car, members associated with the switches, and having arms, the arm of the member associated with the up direction switch serving to hold open the down direction switch, and the arm of the member associated with the down direction switch serving to hold open the up direction switch during the time of control of the elevator by the car switch.
13. In a self-leveling electric elevator, the combination of the car, the hoisting machine, the car switch, the leveling apparatus comprising self-closing car leveling switches, members for said switches, each member having a movable camming arm, one arm for each leveling switch, electro-motive means to move said arms to hold the leveling switches open.
14. In a self-leveling electric elevator, the combination of the car, the hoisting machine, the car switch, the leveling apparatus comprising self closing leveling switches, movable members associated with the leveling switches, one member for each switch, the members each having an arm to hold the leveling switch open with which the other member is associated during the time of the car switch control of the elevator, and means to move the members to cause the arms to hold the leveling switches open.
15. In a self-leveling electric elevator, the combination of the car, the hoisting machine, the car switch, the leveling apparatus comprising self closing leveling switches, movable members associated with the leveling switches, one member for each switch, the members each having an arm to hold the leveling switch open with which the other member is associated during the time of the car switch control of the elevator, and electro-motive means to move the members to cause the arms to hold the leveling switches open.
16. In a self-leveling electric elevator, the combination of the car, the hoisting machine, the car switch, the leveling apparatus comprising self closing leveling switches, movable members cooperatively associated with the leveling switches, one member for a switch, the members each having two arms, one arm to hold the leveling switch open with which the other member is associated, during the time of the car switch control of the elevator, and means to move the members to cause the arms to hold the leveling switches open until the car switch is brought to "off" position, and roller arms and devices in the shaft adapted to engage with the roller arms, one roller arm at a different time from the other roller arm to move the arm which was holding one of the switches open and allow that switch to close to level the car with a desired floor landing and thereafter the roller arm in question to

become disengaged from the cooperating device in the shaft to allow the other arm of the member associated with the same switch to open it and the car to stop level with the desired floor landing.

17. In a self-leveling electric elevator, the combination of the car, the hoisting machine, the car switch, the leveling apparatus comprising two self closing leveling switches, one for up and the other for down direction of travel of the car, two movable members cooperatively associated with the leveling switches one member for a switch, each member having two arms, one arm to hold the leveling switch open with which the other member is associated during the time of the car switch control of the elevator, and means controlled by the car switch to move the members to cause the arms to hold the leveling switches open until the car switch is brought to the "off" position and two roller arms for the leveling switches, one for each switch and devices in the shaft to engage with said roller arms, one roller arm at a different time from the other roller arm to move the arm which is holding one of the leveling switches open to allow said switch to close to level the car with a desired floor landing and thereafter the roller arm for the leveling switch thus closed to become disengaged from its cooperating device in the shaft to allow the other arm of the member associated with the same leveling switch to open that switch for the car to stop level with the desired floor landing, but if the car overruns said landing for the other roller arm to engage its cooperating device in the hatchway and move the other member to cause its other arm to allow the leveling switch associated with said other member to close to bring the car back to said landing, and thereupon the roller arm for the leveling switch last mentioned to become disengaged from its cooperative device in the shaft to allow said other arm of said other member

to open the leveling switch in question to stop the car level with said landing.

18. In a self-leveling electric elevator, the combination of the car, the hoisting machine, the car switch, the leveling apparatus comprised of two self closing leveling switches, one for up and the other for down direction of car travel, two movable members each having two leveling switch operating arms; one arm of each member associated with one and the same switch and the other arm of each member associated with the other switch, one arm of each member adapted to hold open the leveling switches during the time the car switch controls the elevator, means controlled by the car switch to move the members to cause the arms to hold the leveling switches open until the car switch is brought to its "off" position, and two roller arms for the leveling switches and devices in the shaft adapted to engage the roller arms, one roller arm at a different time from the other roller arm, and allow one of the arms which hold the leveling switches open to move to allow one of the leveling switches to close to level the car with the desired floor landing, and thereafter the roller arm for the closed leveling switch to become disengaged from its cooperative device in the shaft to allow the other arm associated with the said closed switch to move to open that switch to stop the car level with the floor landing, but if said roller arm upon disengagement from its cooperative device in the hatchway fail to move to allow the arm associated with the closed switch to open the switch to stop the car, then the other roller arm to engage its cooperative device in the hatchway and move the arm which allowed the switch to close but now to serve to open the switch and stop the car.

In testimony whereof, I have signed my name to this specification.

JOHN E. BOYCE.
